(57) CLAIM

I claim the ornamental design for a jersey, as shown and described.

DESCRIPTION

FIG. 1 is a perspective view of a jersey, showing my new design;

FIG. 2 is a front elevational view thereof, illustrated with a person wearing the design with hands in pockets of the design;

FIG. 3 is a front elevational view of FIG. 1;

FIG. 4 is a right-side elevational view of FIG. 1, the left-side elevational view being a mirror image thereof;

FIG. 5 is a rear elevational view thereof;

FIG. 6 is a top plan view thereof; and,

FIG. 7 is a bottom plan view thereof.

The broken lines showing a person in FIGS. 1 and 2 depict environmental matter and form no part of the claimed design.
